CLAIM

The ornamental design for combined ceiling fan and light fixture, as shown and described.

DESCRIPTION

FIG. 1 is a perspective view of a combined ceiling fan and light fixture showing my new design;

FIG. 2 is a perspective view of the design shown in FIG. 1 with the environmental structure removed therefrom;

FIG. 3 is a front view of FIG. 2;

FIG. 4 is a right-side view of FIG. 2;

FIG. 5 is a rear view of FIG. 2;

FIG. 6 is a left-side view of FIG. 2;

FIG. 7 is a top view of FIG. 2;

FIG. 8 is a bottom view of FIG. 2; and,

FIG. 9 is an enlarged perspective view of the design shown in FIG. 1 with the environmental structure removed therefrom and the included fan blades being shown in fragmentary view.

The broken line showing of environmental structure shown in Fig. 1 is for illustrative purposes only and forms no part of the claimed design.
